Term of patent 14 years

Int. Cl. D27—02

U.S. Cl. D27—07

FIG. 1 is a top plan view of a cigarette holder showing my new design;

FIG. 2 is a left end elevational view;

FIG. 3 is a right end elevational view;

FIG. 4 is a side elevational view;

FIG. 5 is a longitudinal section as taken on the line 5—5 of FIG. 1; and

FIG. 6 is a transverse section as taken on the line 6—6 of FIG. 1.

The bottom plan is a mirror image of the top plan of FIG. 1, and the other side elevation is a mirror image of the side elevation of FIG. 4.

I claim:

The ornamental design for a cigarette holder, as shown and described.
